UNITED STATES PATENT OFFICE.

GEORGE S. SHEPARD, OF LEBANON, NEW HAMPSHIRE.

DESIGN FOR ORGAN-CASES.

Specification forming part of Design No. 7,490, dated June 9, 1874; application filed May 16, 1874.
[Term of Patent 7 years]

To all whom it may concern:

Be it known that I, GEORGE S. SHEPARD, of Lebanon, in the county of Grafton and State of New Hampshire, have invented an Improved Design for Organ and Melodeon Cases, of which the following is a specification:

The nature of my design is fully represented in the accompanying drawing, to which reference is made.

A represents the body of the organ; B, the foundation-board, supporting the reed-boards, keys, &c.; C, a rolling cover, which, in transverse section, is an arc of about ninety degrees of a circle. The foundation-board is supported in front by the scroll-work E E. On the top of the body A is an arched chamber or cover, F,

the back of which is in a line with the back of the body A, while the front is slightly inclined backward. G is a rail, running along the front edge of the cover F, which affords support for the music-book c, which rests against the front of the cover F. H H are lamp-brackets, projecting from the cover F.

What I claim is—

The design for organ or melodeon cases, substantially as described, and shown in the accompanying drawing.

GEORGE S. SHEPARD.
